FISHING ROD HANDLE

Donald M. Kitterman, Kansas City, Kans.

Application February 19, 1951, Serial No. 14,266

Term of patent 14 years

(Cl. D31—4)

To all whom it may concern:

Be it known that I, Donald M. Kitterman, a citizen of the United States, residing at Kansas City, in the county of Wyandotte and State of Kansas, have invented a new, original, and ornamental Design for a Fishing Rod Handle, of which the following is a specification, reference being had to the accompanying drawing, forming a part thereof.

Fig. 1 is a side elevational view of a fishing rod handle, showing my new design.

Fig. 2 is a top plan view thereof.

Fig. 3 is an inverted plan view thereof; and

Fig. 4 is an elevational view of one end of the fishing rod handle.

I claim:

The ornamental design for a fishing rod handle, as shown.

DONALD M. KITTERMAN.
